(57) **CLAIM**

The ornamental design for a belt-mounted, two-way radio holder unit assembly, as shown and described.

DESCRIPTION

FIG. 1 is a right front perspective view of a belt-mount member, in accordance with a first embodiment thereof, of a belt-mounted, two-way radio holder unit assembly.

FIG. 2 is a left front perspective view of the belt-mount member, in accordance with the first embodiment thereof, of the belt-mounted, two-way radio holder unit assembly.

FIG. 3 is a rear elevation view of the belt-mount member, in accordance with the first embodiment thereof, of the belt-mounted, two-way radio holder unit assembly.

FIG. 4 is a bottom perspective view of the belt-mount member, in accordance with a first embodiment thereof, of the belt-mounted, two-way radio holder unit assembly.

FIG. 5 is a left front perspective view of a belt-mount member, in accordance with a second embodiment thereof, of the belt-mounted, two-way radio holder unit assembly.

FIG. 6 is a right rear perspective view of the belt-mount member, in accordance with the second embodiment thereof, of the belt-mounted, two-way radio holder unit assembly.

FIG. 7 is a bottom perspective view of the belt-mount member, in accordance with a second embodiment thereof, of the belt-mounted, two-way radio holder unit assembly.

FIG. 8 is a left front perspective view of a belt-mount member, in accordance with a third embodiment thereof, of the belt-mounted, two-way radio holder unit assembly.

FIG. 9 is a right rear perspective view of the belt-mount member, in accordance with the third embodiment thereof, of the belt-mounted, two-way radio holder unit assembly.

FIG. 10 is a bottom perspective view of the belt-mount member, in accordance with the third embodiment thereof, of the belt-mounted, two-way radio holder unit assembly.

FIG. 11 is a right front perspective view of a radio holder member, in accordance with a first embodiment thereof, of the belt-mounted, two-way radio holder unit assembly.

FIG. 12 is a left rear perspective view of the radio holder member, in accordance with the first embodiment thereof, of the belt-mounted, two-way radio holder unit assembly.

FIG. 13 is a left front perspective view of a radio holder member, in accordance with a second embodiment thereof, of the belt-mounted, two-way radio holder unit assembly.

FIG. 14 is a right front perspective view of the radio holder member, in accordance with the second embodiment thereof, of the belt-mounted, two-way radio holder unit assembly.

FIG. 15 is a top plan view of the radio holder member, in accordance with the second embodiment thereof, of the belt-mounted, two-way radio holder unit assembly; and,

FIG. 16 is a left front perspective view of the belt-mount member, in accordance with the second embodiment thereof, in mated relation with the radio holder member, in accordance with the first embodiment thereof, of the belt-mounted, two-way radio holder unit assembly.

In FIG. 16, the broken lines showing environmental structure of a belt within a belt-mount member and a two-way radio mounted on a radio holder member of the belt-mounted, two-way radio holder unit assembly are for illustrative purposes only and form no part of the claimed design.
